UNITED STATES PATENT OFFICE.

CHAPMAN D. HENRIQUES, OF LARCHMONT, NEW YORK.

CAN-CLOSURE CONSTRUCTION.

Application filed December 21, 1921. Serial No. 523,949.

To all whom it may concern:

Be it known that I, CHAPMAN D. HENRIQUES, a citizen of the United States, and a resident of Larchmont, in the county of 5 Westchester and State of New York, have invented a new and improved Can-Closure Construction, of which the following is a full, clear, and exact description.

This invention relates to a closure construction for cans and receptacles. An object of the invention resides in the provision of a simple, strong, effective but economically manufactured closure construction.

15 Another object resides in the provision of means whereby after the can has been originally filled, a sealing device is placed on the can which can be operated in only one manner to permit the contents of the 20 can to be poured out, and which sealing means cannot be used again.

A further object resides in the particular construction and arrangement of parts whereby after the seal has been broken the 25 closure plug used will when inserted in place form a very tight and effective seal to prevent the spilling of the liquid within the can.

A still further object resides in the particular construction of the spout with relation to the neck of the can or closure whereby as the liquid is being poured out of the 30 can none of it can collect around the neck after the pouring has ceased.

35 Another object resides in the particular construction and arrangement of parts which are hereinafter described and claimed and shown in the accompanying drawings.

The invention is illustrated in the drawings, of which—

Figure 1 is a partial vertical section of the can and construction of closure.

Fig. 2 is a sectional view of the essential elements of the plug portion of the closure.

45 Fig. 3 is a sectional view of the parts of the neck and spout, including the sealing diaphragm.

The form of the invention shown in the drawings is a preferred form, although it is understood that modifications in the construction and arrangement of the parts and in the character of the materials used may be adopted without departing from the spirit of the invention.

55 This invention is applicable to a receptacle such as a can having side walls 1 and

a cover portion 2. This cover portion is provided with the usual handle 3 and an aperture 4 in which the closure construction is disposed.

The closure comprises an interiorly threaded neck-piece or shell 5 (see Fig. 3). Adjacent the upper end of this shell or neck-piece 5 a horizontal flange 6 is formed on the inner edge of which there is an upstanding rib 7. A pouring spout 8 provided with an aperture 9 fits around the rib 7 and rests on the flange 6. When the spout is so disposed, the rib 7 is crimped over, as shown in Fig. 1, to hold the spout on the neck, although the crimping is not tight enough to prevent the rotation of the pouring spout around the axis of the neck.

The spout 8 adjacent the aperture 9 is provided with rather steep walls 10 which flare down close to the upper end of the neck 5. The floor surface 11 of the pouring spout, as can be seen from the above description, and especially the view in Fig. 1, is practically flush with the upper edge of the neck so that in pouring the liquid meets no obstruction from any part of the neck portion since the path of the liquid from the neck through the spout is uninterrupted.

The surface 12 of the cover 2 to which the closure portion is attached is depressed so that when the spout 8 is moved around to permit the end or floor 11 to extend beyond the can for the purpose of pouring the liquid therefrom, when the can is again disposed, after pouring, in normal position the liquid will tend to run back to the rear of the spout 8 and will, therefore, immediately run back into the can because the bottom surface of the spout is flush with the top of the neck 5 and, therefore, there is no possibility of any liquid being trapped. When it is not desired to pour the liquid, the spout is turned around in the full line position shown in Fig. 1 so that the end 11 is out of the way.

I wish also to provide an effective, simple and economically manufactured sealing means normally to be disposed in the aperture 4 until the consumer of the liquid desires to use it. This sealing means comprises a cup-shaped diaphragm 13 having a horizontally extending flange 14 and a reversely curved, vertically tapered flange 15. This diaphragm is to be disposed in the neck 5, as shown in Fig. 1, with the flange 14 resting on a flat surface 16 in the

bottom of the neck 5 by depressing the middle thereof. The side walls 17 of the diaphragm 13 lie parallel to a vertically depending flange 18 on the bottom of the neck 5. This relation is clearly seen in Fig. 1. The flange 14 and the surface 16 can be firmly connected together, if desired, by any suitable process, such as welding or soldering, or they may even be left unconnected except as they are held in position by the plug or cork device to be hereinafter described.

The tapered flange 15 provides a tapered aperture in which a removable seal is disposed. This removable seal comprises a cup-shaped seal of sheet metal, such as 19, with a horizontally extending flange 20. The cup portion of this seal 19 is similarly tapered and adapted to be disposed within the aperture formed by the flange 15. As shown in Fig. 1, this effectively seals the connection between the inner portion of the can and the atmosphere. The seal 19 fits tightly in the aperture formed by the flange 15 and can be removed therefrom only by considerable pressure and only by pushing it into the can. It cannot be removed by pulling it out of the opening formed by the flange 15. In this way, a person wishing to get at the liquid within the can can do so; but after this seal has once been broken, it is impossible to use a similar seal without taking the closure construction completely off the can.

The plug or cork member comprises essentially a threaded hollow shell 21 having a removable cap 22 over which the upper edges of the shell 21 are spun. In the bottom surface 23 of this shell, I provide a cuplike depression 24 formed by depressing the metal of the bottom wall 23. Into this depression 24 the body portion 25 of a cuplike clamping member is to be disposed. The clamping member 25 has an outwardly extending annular flange 26 thereon. When the clamping

member 25 is forced into the recess 24 an annularly shaped washer or packing ring 27 is gripped between the flange 26 and the bottom surface 23 of the shell 21, as shown in Fig. 1. When this arrangement of the parts has been effected, the inner abutting walls of the recess 24 and the member 25 are crimped over, as shown in Fig. 1, to hold the clamping member 25 in position to effectively grip the washer 27. The outer edges of the washer are especially adapted to bear on the flush surface formed by the flange 14 on the adjacent flat surface of the shell 5, so that a very tight joint is here formed to prevent the leakage of fluid from the container after the seal has been broken and the plug is being used.

It will, therefore, be seen that I have provided a simple, efficient, strong, easily manufactured closure construction whereby the objectionable dripping of liquids around the spout of such receptacles is eliminated; whereby an effective joint can be made between the plug or cork and the bottom of the neck after the seal has been broken, or even before, to prevent leakage of the contents of the can.

What I claim is:

A closure construction for cans, which comprises a neck exteriorly threaded and extending above the upper surface of the can, an annular outwardly extending flange near the upper end of the neck, a vertically extending ring adjacent the flange, and a spout having an aperture therein to surround the ring and rest on the flange, the ring adapted to be crimped over to engage the spout, the spout being rotatable around the upper edge of the neck, the floor of the spout being disposed substantially flush with the upper edge of the neck, the spout in one position extending outwardly away from the can, and in the opposite position being disposed within the area of the top surface of the can.

CHAPMAN D. HENRIQUES.
